UNITED STATES PATENT OFFICE.

PERCY GEO. TACCHI, OF NEW WANSTEAD, ENGLAND, ASSIGNOR TO CENTRUM
SYNDICATE LIMITED, OF TOLLINGTON PARK, LONDON, ENGLAND.

ROTATING-CYLINDER INTERNAL-COMBUSTION ENGINE.

1,288,278.

Specification of Letters Patent. Patented Dec. 17, 1918.

Application filed November 9, 1917. Serial No. 201,038.

To all whom it may concern:

Be it known that I, PERCY GEORGE TACCHI, a subject of the King of Great Britain, residing at Bay Tree House, New Wanstead, 5 in the county of Essex, England, have invented certain new and useful Improvements in Rotating-Cylinder Internal-Combustion Engines, of which the following is a specification.

- 10 This invention relates to two stroke internal combustion engines of the type in which rotating cylinders carry pistons that act outwardly against a fixed cam track causing rotation of the cylinders.
- 15 According to this invention the inward or compression stroke of the pistons draws a charge into the fixed engine casing, which charge is then compressed in the casing on the outward or working stroke of the pistons 20 and is admitted to the combustion chamber through an admission valve or valves after the exhaust is opened. In the preferred construction the cylinders open to a common combustion chamber between the pistons and 25 the admission valves are situated between the cylinders and are opened against light spring pressure by the action of the cam track, or when the pressure in the combustion chamber falls on exhaust below the 30 pressure in the casing, which may amount to about 5 lbs. per square inch.

In order that the said invention may be clearly understood and readily carried into effect, I will describe the same more fully 35 with reference to the accompanying drawings, in which:—

Figure 1 is a vertical section of a two piston engine embodying this invention;

Fig. 2 is a part cross section, part end elevation of the said engine.

Fig. 3 is a half elevation, half section of the cylinder casting.

Fig. 4 is a half elevation half section of the cylinder casting at right angles to Fig. 45 3; and

Fig. 5 is a detail section of an exhaust port in the cylinder.

In Fig. 1, for convenience of illustration, the lower part of the cylinder casting is 50 shown as turned through a right angle as

compared with the upper half of the figure which shows a section of the admission valve at the upper side and a longitudinal section through the cylinder and piston at the lower side.

A is the cylinder casting, of circular or disk form in end elevation as shown in Fig. 4, and bored transversely with the cylinder B which forms two opposite cylinder elements receiving the oppositely acting pistons C, between which is the common combustion chamber D. The cylinder casting is fixed upon the hollow shaft L. E is the fixed engine casing made in two halves bolted together. F is the cam track. G, G are 60 the inlet valves. H is a suction valve through which the explosive mixture is drawn into the casing E, the valve rod h being operated at the required intervals by the cam h' on the rotating cylinder casting 65 A. J is a magneto for ignition of the compressed charge in the cylinder B through the sparking plug j.

The cylinder B is provided with a pair of exhaust ports b (one of which is shown 70 in Figs. 4 and 5) extending through a substantial arc and uncovered toward the end of the outward piston-stroke, the exhaust ports leading through one end face a of the cylinder casting A and registering during 75 the exhaust period with corresponding ports e in the fixed engine casing E, which ports open into the exhaust pipes K. The casing is conveniently made in two halves or members bolted together by the bolts e' with the 80 outer edge f of the cam track between the members, an auxiliary cam track F' for moving or holding the pistons out when unsupported by internal pressure being provided at one side, by means of a cam shaped 85 groove in the inner face of the casing E into which a pin or roller c (Fig. 1) on the side of each piston C projects. The auxiliary track F' follows substantially the outline of the main track F. The main cam 90 track F is preferably central and large rollers c' carried by the pistons travel over it, the track, in the case of the two piston engine shown, being symmetrical and usually comprising two rounded ends (preferably 95

each with a part f' concentric with the engine axis to give stationary pistons for part of the revolution) with a straight or slightly curved intervening portion f^2 . The corners 5 f^3 which give the compression stroke are struck from a larger radius than the corners f^4 which terminate the outward stroke of the pistons, see Fig. 2. The cylinder casting A is provided with valve apertures a' 10 between the cylinders and in the same plane, the valve casings g with the inlet valves G being secured in the apertures a' . The valve stems g' project outwardly so as to meet the contracted (straight or slightly curved) portion f^2 of the cam track F during the transfer period when the explosive mixture is being admitted from the casing E to the cylinder B. The valves G are as shown in Figs. 2 and 4 set at an angle, the direction of slope 15 depending on the direction of rotation of the engine. In the valve section in Fig. 1, however, the section is taken through the valve axis for convenience of illustration. The cylinder casting is hollow and water circulates through the cooling space a^2 being supplied through the tube z passing through the hollow shaft L on which the casting is rigidly mounted. The gap or channel a^3 permits of the passage of the track F.

20 The following is the cycle of the two piston engine illustrated:—

Starting with the pistons C at their outermost position, with the cylinder B and valves G in the position shown in dotted lines in Fig. 2, the inlet valves G are open and the exhaust ports b are also fully open but close shortly after the pistons C begin their inward stroke. The stems g' of the inlet valves G then leave the cam track F 25 and the valves close, when compression begins and continues until the pistons are at right angles to the initial position, with the rollers c at the most contracted portion of the cam track. In the meantime a fresh 30 charge has been drawn by the inward movement of the pistons C through the suction valve H into the engine casing E, a carbureter (not shown) being fitted to the bracket h^2 (Fig. 2) on the valve casing h^3 . Ignition 35 of the compressed charge between the pistons C takes place and the working stroke occupies most of the second quarter of the revolution, the piston rollers c pressing outwardly against the expanding portion f^2 , f^4 40 of the cam track. Compression of the new charge in the casing E occurs during the working stroke, up to say 5 lbs. per square inch.

45 Before reaching the end of the outward stroke the double exhaust is opened, the pistons uncovering the ports b at the outer ends of the cylinders, which ports already register with the casing ports e , and the internal

pressure falls. When the pressure falls sufficiently the inlet valves G open (they may 50 open automatically) and the entering charge expels the waste gases in both directions through the exhaust ports. As the charge enters at the middle of the combustion chamber D and drives out the exhaust at 55 both ends, the length of travel of the gases is very small, only about a quarter of the travel of the gases of a single cylinder two-stroke engine of the same power. The valves G are maintained open by the track F but 60 the track is arranged not to open the valves mechanically before the exhaust ports b are well open. At low speeds automatic opening of the valves G would occur but at high speeds the valves might remain closed until 65 mechanical opening occurs. The track F insures full opening of the valves at any speed and also insures the admission of a mixture which may, by reason of throttling, be at too low a pressure to open the valves 70 automatically. The complete cycle occupies only half a revolution so that there are two double piston working strokes at each revolution.

75 This invention has been described more especially as applied to a double-piston engine but it is to be understood that it is not confined to engines with two pistons only.

80 What I claim and desire to secure by Letters Patent of the United States is:—

85 1. In a two stroke rotary cylinder internal combustion engine having a fixed cam track against which a plurality of pistons act, a casing, means for admitting an explosive charge to the said casing on the inward or compression stroke of the pistons, which charge is compressed in the casing by the outward stroke of the pistons, a non-return valve admitting the compressed charge 90 to the working space of the cylinder and means for opening the said valve after the exhaust has been opened.

95 2. In an engine as claimed in claim 1, a member on the aforesaid admission valve, adapted to meet the cam track and to open 100 the valve, after the opening of the exhaust, under the control of the said track.

105 3. In a two stroke rotary cylinder internal combustion engine having a fixed cam track, a rotary cylinder casting, a diametrical cylinder formed in the said casting, a pair of oppositely acting pistons in the said cylinder, open to a common combustion chamber and acting outwardly against the 110 said cam track, a fixed casing inclosing the cylinder casting and providing a space for admission and compression of an explosive charge during the inward and outward piston strokes respectively, an inlet valve in the cylinder casting opening the casing space 115 to the combustion chamber and means for 120 125

opening the said valve after the exhaust has been opened, for the purpose specified.

4. In an engine as claimed in claim 3, wherein the cylinder casting is of disk form and has inlet valve apertures at right angles to the diametrical cylinder and a pair of exhaust passages extending from the cylinder to openings in one end face of the said casting, and the fixed casing is of disk form and has exhaust ports in one side adapted to register with the ends of the exhaust passages in the cylinder casting during the exhaust portion of the engine stroke.

PERCY GEO. TACCHI.
